UNITED STATES PATENT OFFICE.

CLARENCE E. SAFFORD, OF LANCASTER, NEW YORK.

RADIATOR.

SPECIFICATION forming part of Letters Patent No. 355,216, dated December 28, 1886.

Application filed February 18, 1886. Serial No. 192,402. (No model.)

To all whom it may concern:

Be it known that I, CLARENCE E. SAFFORD, of Lancaster, in the county of Erie and State of New York, have invented new and useful 5 Improvements in Radiators, of which the following is a specification.

This invention relates to improvements in that class of radiators which consist of a series of vertical sections connected at their top and 10 bottom, through which the steam or other heating agent circulates.

The object of my invention is to improve the 15 construction of this class of radiators, whereby a greater radiating or heating surface is presented to the apartment to be heated without materially increasing the size of the radiator.

The invention also relates to improvements in the construction of the coupling-tubes, whereby the sections are secured together.

20 The invention consists, to these ends, of the improvements which will be hereinafter described, and pointed out in the claims.

In the accompanying drawings, Figure 1 represents a side elevation, partly in section, of my 25 improved radiator. Fig. 2 is a vertical cross-section of the same. Fig. 3 is a horizontal cross-section in line *x*, Fig. 1, on an enlarged scale. Fig. 4 is an end view of the lower portion of one of the sections on an enlarged scale. Fig. 5 is a fragmentary sectional elevation, on 30 an enlarged scale, showing the manner of connecting two sections together. Fig. 6 is a side elevation, on an enlarged scale, of one of the coupling-tubes. Fig. 7 is an end view thereof. Fig. 8 is an end view of one of the coupling-tubes slightly modified.

Like letters of reference refer to like parts in the several figures.

A A' A² represent the vertical radiator-sections, each of which consists of a hollow base portion, *a*, having a curved or semicircular bottom, *a'*, a top chamber, *b*, and a series of vertical radiating-tubes, *C*, connecting the top and base chambers and cast in one piece therewith. The vertical tubes *C* form a communication between the base and top chambers of each section, and the tubes *C* of each section are connected between the top and base portions by short horizontal tubes *d*. The short 45 horizontal tubes *d* form braces which strengthen the vertical radiating-tubes *C*, and also form 50 communications between the series of tubes *C* of each section.

The radiating-tubes *C* are flattened or elongated in cross-section, as shown in Fig. 3, and 55 the flat or wide sides of the two outer tubes of each section form the sides of the radiator. By arranging the radiating-tubes *C* in this manner a much larger radiating surface is presented to the apartment to be heated than when the tubes 60 are arranged with the narrow ends outward, thereby increasing the outer radiating surface of the radiator.

The chambers *a* and *b* of each section are provided with threaded openings *e*, which are 65 formed on opposite sides of the chambers and in line with each other.

f are annular shoulders or flanges formed on opposite sides of the chambers *a* and *b*, and surrounding the openings *e*.

70 G represents screw-threaded couplings which connect the several sections together, and which are screwed into the openings *e*. The couplings *G* are each provided with external right and left hand screw-threads *g g'*, which 75 are separated by an annular groove, *g²*, depressed below the screw-threads, as shown in Fig. 6. This groove facilitates cutting the right and left hand threads, enables the radiator-sections to be drawn closely together, and 80 accommodates a suitable packing between the sections. The couplings *G* are hollow, and form a communication between the respective chambers *a* and *b* of the several sections. The couplings *G* are provided on their inner surface with inwardly-projecting lugs *h*, having 85 straight or flat faces *h'*, whereby the couplings can be readily turned in the openings *e* by inserting a wrench or other suitable tool, *I*, into the bore of the coupling. The screw-threads 90 in the two adjacent openings *e* of the several sections correspond with the screw-threads formed on the couplings *G*, one being a right-hand thread and the other a left-hand thread, so that when a coupling is arranged between 95 the two adjacent openings, as shown in Fig. 5, and the wrench *I* inserted in the bore of the coupling, the latter can be readily screwed into the openings *e e* of the two sections by turning the wrench. The couplings *G* are screwed into 100 the openings *e* until the shoulders or flanges *f* of the two adjacent openings abut against each

other, whereby a perfectly-tight joint is formed between the two adjacent sections and the sections firmly secured together. If desired, a suitable packing may be inserted between the flanges or shoulders *f*. The bore of the couplings *G* may be of any suitable or desirable shape that will permit their being turned by inserting a suitable tool or wrench. Constructing the couplings *G* with flat sides, or of any other irregular shape that will permit them to be turned, as described, enables the sections to be secured together at their top and bottom without disturbing the position of the sections, and also enables the sections to be readily disconnected when desired.

When the sections have been secured together, they are supported in a vertical position upon legs *J*, which are cast or formed on the two end sections, *A'A²*, which are also provided with the inlet and outlet pipes *k'k*, respectively, through which the hot water or other heating agent employed circulates through the radiator. The bore in the coupling *G*, which connects the bottom chambers of the end section *A'* and the adjacent section, *A*, is provided with a partition, *l*, which closes the communication between the two lower chambers of these sections, and causes the heating agent employed to be deflected upward in the end chamber *A'*, through the vertical radiating-pipes *C*, to the top chamber, *b*, and through the top chambers in the remaining sections and downward through the vertical radiating-tubes *C* until it escapes through the outlet-pipe *k'* in the bottom chamber of the

end section *A²*. The tops of the several sections are covered by an ornamental top plate, *M*, which is secured to the end sections, *A'A²*, by bolts *m*.

I claim as my invention—

1. The combination, in a radiator, of a series of vertical sections, *A*, each composed of a bottom chamber, *a*, a top chamber, *b*, and vertical radiating-tubes *C*, made oblong in cross-section and connecting said top and bottom chambers, and arranged with their flat or wide sides outward, and horizontal tubes *d*, connecting the vertical tubes *C* between the bottom and top chambers, substantially as set forth. 40

2. In a radiator, the combination, with two radiating-sections, of a hollow coupling, *G*, provided on its outer side with right and left screw-threads, and on its inner side with holding-surfaces for the reception of a tool or wrench, by which the nipple can be turned, 45 substantially as set forth. 50

3. In a radiator, the combination, with two radiating-sections, of a hollow coupling, *G*, provided on its outer surface with right and left hand screw-threads *g'g*, separated by an 60 annual groove, *g''*, which is depressed below the screw-threads, and on its inner side with holding-surfaces for the reception of a wrench, substantially as set forth.

Witness my hand this 10th day of February, 65
1886.

CLARENCE E. SAFFORD.
